US00D827843S

(12) **United States Design Patent** (10) Patent No.: **US D827,843 S**
(45) Date of Patent: ** Sep. 4, 2018

(54) **SKIN TREATMENT DEVICE**

(71) Applicant: **Reckitt Benckiser (Brands) Limited**, Slough (GB)

(72) Inventors: **Michael Bainton**, Warwick (GB); **Peter Kay**, Warwick (GB); **Norman Stevenson**, Warwick (GB)

(73) Assignee: **RECKITT BENCKISER (BRANDS) LIMITED**, Slough (GB)

(**) Term: **15 Years**

(21) Appl. No.: **29/609,785**

(22) Filed: **Jul. 5, 2017**

(30) **Foreign Application Priority Data**

Jan. 10, 2017 (EM) 003616309-0003

(51) **LOC (11) Cl.** **28-03**

(52) **U.S. Cl.**

USPC **D24/200**

(58) **Field of Classification Search**

USPC D24/107, 133, 147, 186, 200, 209, 210, D24/211, 214, 215

CPC A61B 5/441; A61B 5/442; A61B 5/443; A61B 5/444; A61B 5/445; A61B 18/203; A61B 5/0008; A61B 5/01; A61B 1/227; A61N 5/0616; A61N 5/062; A61N 5/0613; A61N 2005/0644; A61F 7/007; A61F 2007/0086; A61F 2007/0087; G01K 5/22; G01K 13/00

(74) Attorney, Agent, or Firm — Troutman Sanders LLP; Ryan Schneider; Chris Davis

(57) **CLAIM**

The ornamental design for a skin treatment device, as shown and described.

DESCRIPTION

FIG. 1 is a perspective view of our new design for a skin treatment device;

FIG. 2 is a back elevation view thereof;

FIG. 3 is a front elevation view thereof;

FIG. 4 is a left side elevation view thereof;

FIG. 5 is a right side elevation view thereof;

FIG. 6 is a top plan view thereof; and,

FIG. 7 is a bottom plan view thereof.

1 Claim, 4 Drawing Sheets
